UNITED STATES PATENT OFFICE.

JOHN G. SMITH, OF ST. LOUIS, MISSOURI.

FOLDING COT.

SPECIFICATION forming part of Letters Patent No. 408,141, dated July 30, 1889.

Application filed March 26, 1887. Serial No. 232,526. (No model.)

To all whom it may concern:

Be it known that I, JOHN G. SMITH, of the city of St. Louis, in the State of Missouri, have invented certain new and useful Improvements in Folding Cots, of which the following is a full, clear, and exact description, reference being had to the accompanying drawings, forming part of this specification, and in which—

10 Figure I is a perspective view of the cot in using position. Fig. II is an enlarged view folded. Fig. III is a top view folded. Fig. IV is an enlarged perspective view of part of one of the hinges. Fig. V is an enlarged detail view of the frame and the hinge attached. Fig. VI is an enlarged detail view showing a section of the inside of the frame with leg and brace attached. Fig. VII is an enlarged detail side view showing the position of a leg and brace when folded. Fig. VIII is a view of leg and brace folded, showing part of the frame.

25 My invention relates to the construction of folding cots; and my invention consists in features of novelty hereinafter fully described, and pointed out in the claims.

30 Referring to the drawings, 1 represents the frame, 2 the legs, and 3 the braces, one end of which is attached to the legs and the other to the body of the frame, thus holding the legs in using position. The braces have "rule-joints" 4, permitting them and the legs to be folded.

35 The frame is constructed in three sections, the two end sections being made to fold upon the center one, and they are connected to the center section by hinges, consisting each of two triangular portions 7, one part of each hinge being secured to the middle part of the 40 cot by rivets 8, and the other part of each hinge is connected to an end section by rivets 9. The two parts of each hinge are secured together at top by a pin passing through per-

forations 10, and the lower points of the two parts of each hinge come together, Fig. V, and by thus abutting, take the entire strain of the pressure brought upon the ends of the cot, there being a space 12 between the body and each end when the latter is in using position. (See Fig. VI.) The lower ends of the hinges 45 are perforated at 11; but this is for the purpose of making duplicates of them, so that they can be placed on either side of the cot, and not for the purpose of connecting them at this point. The extreme lower end 20 of 50 one member of each hinge rests against a shoulder 21 of the adjacent end of the other member, this shoulder being shown plainly in Fig. IV and by dotted lines in Fig. V.

I claim as my invention—

1. In combination with a cot consisting of a central portion and end wings, the hinges fixed to the sides and connecting the end wings to the central portion, so that they may be folded thereon, said hinges consisting of 65 two parts, each connected at the top of the cot at 10 and having abutting ends at the bottom of the cot, whereby the ends are adapted to fold over on top of the cot, substantially as set forth.

2. In combination with a cot consisting of a central portion and end wings having spaces between the contiguous ends, the hinges connecting the end wings to the central portion, so that they may be folded thereon, said 75 hinges consisting of two triangular pieces having openings at 10 and 11 to receive pivot-pins, depending on which side of the cot the hinges are placed, said pieces being pivoted together at the top of the cot and having abutting lower ends, substantially as set forth.

JOHN G. SMITH.

In presence of—
GEO. H. KNIGHT,
JOSEPH WAHLE.
